UNITED STATES PATENT OFFICE.

CHARLES F. STODDARD, OF NEW YORK, N. Y., ASSIGNOR TO AMERICAN PIANO COMPANY, OF NEW YORK, N. Y., A CORPORATION OF NEW JERSEY.

AUTOMATIC MUSICAL INSTRUMENT.

Application filed March 12, 1924. Serial No. 698,599.

This invention relates to automatic musical instruments such for instance as pianos; and it pertains more particularly to expression devices for such instruments, or to 5 means for governing playing intensities.

Among other objects, the invention is intended to provide apparatus capable of reproducing with great fidelity the manual performances of pianists and to reenact interpretations of musical compositions as rendered by well known artists of ability.

It is an object of this invention not only to reproduce accurately the various gradations of dynamic force with which the notes 15 of a musical composition are sounded, but also to reflect the mood and spirit of the manual performer, and thereby to give life and contrast to the mechanical rendition which shall make it approximate manual 20 rendition even more closely than has been possible before.

It is a further object to embody the invention in apparatus which is very simple and reliable in operation.

25 Other objects and advantages of the invention will appear hereinafter.

For illustration, the accompanying drawings show one practical embodiment of the invention employing suitable pneumatically 30 governed devices in cooperation with a piano action; but, as will appear to those skilled in the art, the invention is susceptible of embodiment in various constructions and organizations other than that particularly 35 shown and described herein. It will appear likewise that it is not indispensable that all the features of the invention be used conjointly, since their respective substantial 40 advantages may accrue from their separate application in any practicable manner to a suitable playing intensity.

Figure 1 is a semi-diagrammatic view of the apparatus.

Figure 2 is a side elevation of the source 45 of pneumatic power, parts of the apparatus being broken away and parts being shown in section to better disclose the construction and operation.

50 Figures 3, 4, 5 and 6 are side elevations of a portion of the apparatus showing the parts under various operating conditions.

Referring to the drawings, a striker or player pneumatic 1 is provided having a

sticker 2 to act upon a wippen 3 and thereby operate the usual piano action, as is well 55 understood in the art. A wind trunk 7 leads to a wind chest for the motor pneumatics, each of which has a secondary valve 8 controlled by a primary valve 9 operated from a tracker board 10 through a duct 11 in the 60 usual manner.

The wind trunk 7 communicates with a regulated wind chest 12. A high exhaust chest 14, arranged for communication with the chest 12, may be connected by a trunk 15 65 with a source of pneumatic exhaust 16 which will be more particularly described herein-after.

It is to be understood in the following description that where the term "pressure" 70 is used, pressures in their absolute sense are referred to,—that is, relative to zero pressure or absolute vacuum as a base. However, due to the fact that sub-atmospheric pressures are commonly measured on a water-gauge, which assumes atmospheric pressure as a base value, the term "exhaust" will 75 be used at times, to avoid confusion, in its normal sense of vacuum or subatmospheric pressure. Thus, high exhaust is high 80 vacuum, or low pressure; and as exhaust increases, pressure decreases and conversely.

In the illustrative apparatus of the drawings, the striker pneumatics 1 may be operated by the exhaust in the regulated exhaust chest 12. In order to vary the operation of the striker pneumatics to thereby 85 vary playing intensities, this regulated exhaust may be varied by subjecting it more or less to the influence of high exhaust in 90 chest 14. For this purpose there has been provided between the high exhaust chest 14 and the regulated exhaust chest 12, a port 30 controlled by throttle valve 31.

For purposes of simplicity of description, 95 a single regulated exhaust chest has been illustrated which controls the pressures throughout the action chest of the piano. As will be understood by those skilled in the art, however, the action chest of automatic 100 musical instruments is frequently divided into bass and treble sections, in which case a separate regulated exhaust chest and controlling valves and pneumatics may be provided for each section in the usual manner.

The valve 31 may be operated by a variety 105

of different means. In this specific apparatus there has been selected for purposes of illustration the apparatus disclosed and described in a prior patent to Charles F. Stoddard, No. 1,409,492, patented March 14, 1922.

As set forth in the aforementioned patent, apparatus embodying the invention disclosed therein has a three-fold capacity for controlling the valve 31. It produces automatically incremental changes in playing intensities; it performs a regulating function,—that is, it maintains any given playing intensity whether one or many notes be sounded; and it produces automatically continuously progressive changes in playing intensities for the purposes of producing crescendo and diminuendo effects.

As is also set forth in the aforementioned patent, in the operation of the specific illustrative apparatus the board 33 and valve 31 are constantly under the control of opposed forces tending always to balance each other and hold the valve 31, as it were, in suspension between them; that is to say, the specific apparatus tends constantly to establish a balancing equation between the opposed forces acting upon the valve 31. Such movement of the valve 31 as may occur when that balancing equation is disturbed takes place practically instantaneously so that a new balancing equation appropriate to the newly initiated conditions is immediately set up.

The actual variation of regulated pressure may result from a number of causes, or a combination of causes, such that the valve 31 may or may not be moved to assist in a reestablishment of the pressure equation above referred to, which holds the valve in balance.

While it is preferable with such apparatus that the means of the present invention is combined, yet it will be apparent that other apparatus having any one or all of the capacities of the apparatus of the aforesaid patent may be combined therewith to advantage. As the description proceeds, it will be obvious that the invention is not dependent upon the specific details of construction or the specific mode of operation of the apparatus herein described, but that it resides as well in the broad underlying concepts which will be referred to more particularly hereinafter.

For the purposes of the present description it may be assumed temporarily that the valve 31 is being held in equilibrium by the opposed forces before mentioned. In the aforementioned patent it was assumed that high exhaust was maintained at a substantially constant level during the operation of the instrument. The present invention, however, concerns itself with not only maintaining high exhaust at a substantially constant level when so desired, but also with

varying the degree of exhaust applied to the high exhaust chest 14.

Before proceeding to a consideration of the specific means employed to accomplish this purpose, it may be convenient to consider the effect that such variations in high exhaust will have on playing intensities.

In the aforementioned patent it was explained that the pneumatic forces acting on the valve 31 might be resolved into two groups of opposed forces, those tending to give an upward pull to the valve, and those tending to give a downward pull to the valve. The forces tending to give a downward pull to the valve consisted of the differential between atmospheric pressure on the top of the board 33 and the lesser regulated pressure in one or more of the pneumatics, plus the pressure of high exhaust in the chest 14 acting on the area of the valve 31 itself. The forces exerting an upward pull consisted of the force exerted by the pneumatic 37, plus the force of the regulated pressure in the chest 12 on the area of the valve. The regulated pressure being greater, it predominates and the resultant effect upon the valve area itself is an upward pressure which combines with the resultant of the pressure in the several pneumatics to control the valve 31.

In any such system wherein the pressure of high exhaust constitutes a factor in such a pressure equation, and assuming temporarily that the operative areas of the various pneumatics remain constant, it will be apparent that if the pressure of high exhaust is changed, a reestablishment of the pressure equation above referred to must necessarily result and the pressure of regulated exhaust must also change. For instance, assuming that an exhaust represented by a water gauge pressure of twenty inches be considered as normal exhaust, if the exhaust is decreased to say twelve inches, regulated exhaust must also decrease in order to maintain the pressure equation and the valve in a balanced condition. Conversely, if high exhaust be increased from twenty inches to say thirty inches on the water gauge, regulated exhaust must be increased in order to maintain the pressure equation and the valve in balanced condition.

Such fluctuations in the pressure of high exhaust may or may not result in movement of the valve 31. Normally, that is, when the valve is in equilibrium, and none of the motor pneumatics 1 are being operated to sound the notes of the piano, a decrease in the degree of high exhaust from twenty inches to ten inches would be accompanied by a closing movement of the valve 31 to prevent the passage of some of the air from the regulated exhaust chest in order to decrease the exhaust therein. On the other hand, if at the same time that high exhaust

- was being decreased, a large number of motor pneumatics 1 were being operated and thus admitting a quantity of atmospheric air to the regulated exhaust chest 12, such 5 closing movement of the valve 31 would be minimized or even prevented entirely. Under extreme conditions, indeed, it is possible that an opening movement might be necessary.
- 10 Conversely, under normal conditions if high exhaust is increased, the valve 31 would normally tend to an opening movement, although this again might be negated by a sudden decrease in the number of motor 15 pneumatics being operated.
- To sum up, an increase in the pressure of high exhaust causes an increase in the pressure of regulated exhaust; and a decrease in the pressure of high exhaust causes 20 a decrease in the pressure of regulated exhaust. And these changes in the pressure of regulated exhaust, it will be observed, occur throughout the entire range of playing intensities. That is, whatever the pressure 25 of regulated exhaust may be, a change in the pressure of high exhaust will cause a change in the pressure of regulated exhaust.
- For instance, for convenience of description and explanation it may be assumed that 30 the playing intensities determined by the crescendo, diminuendo and incremental or step change mechanism could be measured by an imaginary scale upon which the numeral 5 would indicate the lowest playing 35 intensity, while the numeral 20 would indicate the loudest playing intensity when high exhaust is being maintained at twenty inches. Therefore, incremental, crescendo and diminuendo changes will be effected 40 within the compass of this scale from 5 to 20. For instance, it may be assumed that the seven steps would fix the different playing intensities respectively at 5, 5.7, 6.7, 8, 10.8, 16.5 and 20.
- 45 It may further be assumed that a crescendo may be inaugurated when the playing intensity is fixed at any one of the seven points in the scale except the last, and will in operation, if continued long enough, raise 50 the playing intensities at a greater or less speed as may be determined by the apparatus, from the point at which it is inaugurated to the highest intensity.
- Thereafter a diminuendo operation may 55 be inaugurated to decrease playing intensities to any point determined by the step change mechanism.
- If now high exhaust be decreased from 60 twenty to twelve inches regulated exhaust would be decreased and playing intensities thereby decreased throughout the entire range of the imaginary scale. For instance, the lowest normal intensity 5 on the imaginary scale would be decreased to 4 and the 65 normal intensity of 5.7 would be decreased to 4.5 and so on, so that the new scale of playing intensities might be represented by 4, 4.5, 5, 6.2, 8.2, 11.7 and 12.
- On the other hand, if high exhaust is increased from twenty to say twenty-five and one half inches, regulated exhaust would be correspondingly increased and playing intensities increased. For instance, the imaginary scale under these conditions may be as follows: 5.5, 6.5, 7.7, 9.5, 12.7, 19 and 75 25.5. Similarly, further increase in high exhaust would result in further increase in playing intensities, as for instance, if high exhaust be increased to thirty-five and one half inches, the imaginary scale might be as follows: 7.7, 8.7, 10, 12, 16, 24 and 35.5. Obviously, the foregoing figures are presented herein for illustrative purposes only, it being desired merely to show that the change in the pressure of high exhaust tends 80 to change the entire range of playing intensities.
- In the present embodiment, means have been provided to vary the pressure in the high exhaust chest 14 by controlling the exhaust produced by the source of power. Referring more particularly to Figure 2, the suction pump 16 is provided with a regulator bellows 201 which is in free communication 90 with the exhaust chamber 202 of the pump through passages 203. The reservoir bellows comprises a fixed leaf 204 which may be conveniently mounted on the outside of the pump as shown, and a movable leaf 205, the bellows being urged toward open position by 95 means of a leaf spring 206.
- The exhaust chamber 202 of the pump is also in free communication with a valve chamber 210 formed in the block 211 by means of a passage 212. A valve 213 is 100 mounted on a valve stem 214 and is held in position against the valve seat 215 by means of a helical spring 216. Free passage of atmospheric air is permitted to the valve chamber 210 when the valve is open through 110 the passages 217 and 218, the passage 218 being open to atmosphere in the interior of the pump, it being understood that the interior is constantly open to atmospheric air through openings 221. Pieces of felt 219 115 and 220 may be inserted in passages 217 and 218 respectively to muffle the sound of air passing through the passages.
- When the motor 225 is started to operate 120 the source of pneumatic power 16, air is withdrawn in a well-known manner by four bellows 226, thereby reducing the pressure and creating a partial vacuum in the exhaust chamber 202, which exhaust is communicated to the high exhaust chest 14 125 through the passage 15 as before set forth.
- If it is assumed for the moment that no movement of the valve 213 takes place, operation of the pump will produce the highest exhaust within the capacity of the 130

pump. It will be apparent, however, that movement of the valve 213 away from its seat will permit the flow of atmospheric air into the exhaust chamber 202 to thereby reduce the degree of high exhaust. It will also be observed that exhaust in the exhaust chamber 202 will also tend to collapse the regulator pneumatic 201 against the force of its spring 206, the greater the exhaust in the chamber 202, the greater being the collapse of the pneumatic 201.

Neglecting for the moment the specific form of connection between the regulator bellows 201 and the valve stem 214, and assuming that some direct connection is present, it will be apparent that closing movement of the pneumatic 201 will move the valve 213 away from its seat to admit atmospheric air to the exhaust chamber 202.

The effect of this action will be to maintain the pressure in the exhaust chamber 202 at a substantially constant level. If the degree of exhaust tends to increase, the regulator pneumatic 201 will tend to collapse and due to its connection with the valve stem 214, the valve 213 will admit atmospheric air to the chamber 202 to thereby tend to decrease the degree of exhaust. Conversely, if the exhaust in the exhaust chamber 202 tends to decrease, the regulator pneumatic 201 will tend to expand to draw the valve 213 more closely to its seat to admit less atmospheric air to the exhaust chamber 202, and the degree of exhaust therein will thereby tend to be increased.

It will be understood, therefore, that in the case of the valve 213, as in the case of the valve 31, an equilibrium is set up and maintained between the forces tending to open the valve and the forces tending to close the valve which maintain it in a substantially balanced condition.

Means are provided for connecting the movable leaf 205 of the regulator pneumatic with the valve stem 214, such means comprising preferably means for varying the operative relationship therebetween in order to secure varying effects.

Pneumatics 230 and 231 are mounted on the movable leaf 205 of the regulator pneumatic 201, and the pneumatic 231 is provided with an abutment 232 which projects upwardly into position for engagement with a collar 233 mounted on the valve stem 214. The valve stem 214 may conveniently be pivoted as at 234. The pneumatic 201 is provided with a limit stop 235 which is fixed to a board 204 and extends over and engages the outer face of the movable board 205. A limit stop 236 is also provided for the pneumatic 230 which is fixed to the leaf 205 and extends over and engages the outer face of the leaf 237 by means of an adjustable screw 238. A limit stop 239 is also provided for the pneumatic 231 which is fixed to the leaf

240 and extends over and engages the leaf 237 by means of an adjustable screw 241. The extent of movement of each of the pneumatics 230 and 231 may be conveniently adjusted by the set screws 238 and 241.

When the pneumatics 230 and 231 are in expanded condition, the limit stops 236 and 239 cause the leaf 240 to move with the leaf 205 of the regulator bellows 201 and transmit motion of the leaf 205 to the valve stem 214 as soon as the regulator pneumatic 201 is sufficiently collapsed to cause the abutment 232 to engage the collar 233. When both of the pneumatics 230 and 231 are in expanded condition, this engagement will not occur until the regulator pneumatic 201 is nearly collapsed as illustrated in Figure 4. On the other hand, when the bellows 230 and 231 are both collapsed, a very slight movement of the regulator bellows may cause such engagement as illustrated in Figure 3. By providing bellows 230 and 231 with different opening movements, two different intermediate positions may be secured as illustrated in Figures 5 and 6 in which, as there illustrated, engagement between the abutment 232 and the collar 233 will occur in two different positions of the leaf 205.

In each of these positions of the regulator bellows 201 a different condition of equilibrium will be set up due to the fact that in each position the spring 206 exerts a different opening force on the leaf 205. In its wide open position, as in Figure 3, the spring exerts its least degree of pressure, while in its closed position as illustrated in Figure 4 the spring being under a greater degree of compression exerts a greater force.

The result of such operations on the pressures in the exhaust chamber 202 will now be apparent. When the pneumatics 230 and 231 are caused to assume the position of Figure 3, the degree of exhaust in the exhaust chest 202 will be at a minimum, and conversely, when the pneumatics 230 and 231 are caused to assume the position of Figure 4, the degree of exhaust in the exhaust chest 202 will be at its highest level. When the pneumatics are caused to assume the positions of Figures 5 and 6, intermediate pressures are secured in the exhaust chest 202. In any one of the four positions illustrated the regulator bellows 201, of course, will control the valve 213 to maintain the pressure established at a substantially constant level, and it will continue to do so until a change in the positions of the pneumatics 230 and 231 causes a new condition of equilibrium to be set up.

Means are provided for controlling the operation of the bellows 230 and 231 automatically from the tracker bar. Referring to Figure 1, a valve block 250 is provided in which are mounted an outside valve 251 and an inside valve 252 which may be operated

5 by diaphragms 253 and 254 respectively. An exhaust chamber 255 is provided which is constantly maintained under exhaust by means of the passage 256 connected to the exhaust chamber 202. When the valves are in their normal seated position, as illustrated in Figure 1, the passage 257 to the pneumatic 230 is open to atmospheric air through the port 258 and the pneumatic 230 remains 10 therefore in expanded condition. On the other hand, the passage 259 is subjected to exhaust from the exhaust chamber 255 and the pneumatic 231 therefore is normally maintained in collapsed position.

15 The normal position, therefore, of the pneumatics will be as illustrated in Figure 5, and the normal degree of exhaust in the exhaust chamber 202 will be at the first step above its minimum. If, under these 20 conditions, atmospheric air is admitted to the diaphragm chamber 261 through the passage 262, the valve 252 will be raised cutting off the passage of atmospheric air through the port 258 and allowing suction 25 through the passage 263 to collapse the pneumatic 230. Under these conditions the pneumatics assume the position of Figure 3, both of the pneumatics 230 and 231 being collapsed, and the degree of exhaust in the 30 exhaust chamber 202 will be at a minimum.

If, under these conditions, atmospheric air is admitted to the diaphragm chamber 265 through the passage 266, valve 251 will be raised, exhaust from the chamber 255 35 will be cut off, and atmospheric air will be allowed to enter the pneumatic 231 through the port 267 to thereby expand the pneumatic. The pneumatics will then assume the position of Figure 6 and the degree of exhaust in the chamber 202 will be somewhat increased. By manipulation of the valves 251 and 252 through the admission of atmospheric air to the passages 262 and 266 the pneumatics 230 and 231 may be 40 controlled at will to cause them to assume the positions of Figures 3, 4, 5 and 6 to thereby establish and maintain varying degrees of exhaust in the high exhaust chest 14 as before set forth.

45 The valves 251 and 252 are in effect secondary valves and may be conveniently controlled by primary valves 270 and 270^a mounted in valve chests 271 and 271^a. Since these valve mechanisms are duplicates only one will be described in detail herein. The valve 270 is normally seated to cover the port 272 to prevent the admission of atmospheric air to the passage 266. Movement of the valve is controlled by a diaphragm 273 which is operated by the admission of atmospheric air to the diaphragm chamber 274 through the duct 275 to the tracker bar. When atmospheric air is admitted to the duct 275 by the uncovering of the tracker vent 276 through an open-

ing in the note sheet, the valve 270 is raised and atmospheric air is admitted to the duct 266 to operate the secondary valve.

When the valve 270 is once open by venting the tracker duct 275, the valve preferably continues open even though the tracker vent may be immediately closed. In the specific apparatus this results from the fact that simultaneously with the operation of the valve 270, atmospheric air is admitted 70 past the valve 270 to a duct 277 through a bleeder vent 278 and through the duct 279 to the diaphragm chamber 274. The chamber 280 is connected to high exhaust through the passage 281 and the continued admission 75 of atmospheric air through the duct 279 to the diaphragm chamber 274 will cause the valve 270 to remain in raised position.

80 From the preceding description it will be apparent that small perforations in a music sheet may be employed to open the tracker vents 276 and 276^a which may be immediately closed if desired.

85 In order to nullify the action just described and to cause the valve 270 to again seat, the valve 285, controlled by the diaphragm 286, may be operated. If valve 285 is raised, the continued passage of atmospheric air to the diaphragm chamber 274 90 is prevented due to the closing of communication between ducts 277 and 279 and the valve 270 immediately drops back to its seat.

95 As has been described in Patent No. 1,409,-492 before referred to, a single cancel valve 84 is provided to cancel the effects caused by setting the valves 58, 58^a and 58^b through the admission of atmospheric air to the duct 86. In the present embodiment this feature has 100 been combined with the present apparatus to cause the cancel valve 84 to return the valves 270 and 270^a to normal position. Duct 287 is provided opening into the channel 86, the result being that when the valve 105 84 is raised to admit atmospheric air to the duct 86, the valve 285 is operated to cause the valve 270 to return to normal position. When the duct 86 is subjected to exhaust, 110 valve 285 remains in seated position.

115 The operation of the apparatus will be apparent from the foregoing description. To sum up, however, valves 270 and 270^a are controlled by openings in the note sheet to operate the pneumatics 230 and 231 to cause 120 varying pressures to be established in the chamber 202 and in the high exhaust chest 14. Such pressures, when established, are maintained at a substantially uniform level by the regulating action of the regulator bellows 201. In normal operation, that is, with tracker vents 276 and 276^a both closed, the pressure of the exhaust may conveniently 125 be maintained at an intermediate level in order that pressures both below and above 130

6 this level may be established by proper openings in the note sheet. Such changes in pressure being established in the high exhaust chest 14 also effect changes in playing 5 intensities as before described. The step change mechanisms, however, operated by the bellows 34, 35 and 36, and the crescendo apparatus, however, maintain their respective capacities to produce step changes and 10 crescendo changes whatever the pressure established in the high exhaust chest may be. The step changes and the crescendo changes established, however, will vary depending on the particular pressure established in the 15 high exhaust chest as will be understood.

The capacity of the apparatus to produce variation in tone intensities in the instrument, it will be observed, has a wide range. For instance, in the illustrative prior art 20 apparatus forming a part of the present combination, it was possible to obtain a scale of seven grades or steps of playing intensities, whereas with the present apparatus it is possible to obtain four different scales of 25 seven grades or steps. It is furthermore possible with the apparatus herein described to shift immediately from one range of playing intensities to a different range as for instance from an imaginary scale of intensities ranging from 4 to 12 to another range 30 from 7½ to 35½.

The similarity of this capacity to actual playing conditions in the rendition of musical compositions manually may be mentioned. In manual playing the performer, 35 when playing a forte or fortissimo passage, frequently assumes, either consciously or unconsciously, an attitude of tenseness, and while various grades of tone intensities may be noticed as the passage proceeds, as for 40 instance the melody notes may stand out more prominently than the accompaniment notes, yet in general the rendition is characterized by brilliance or contrast. Similarly, 45 when the performer is playing a piano or pianissimo passage the pervading spirit is that of delicacy even though certain notes may stand out above the others. So, in the 50 operation of the present apparatus, when the degree of exhaust in the high exhaust chest is increased, a feeling of tenseness may be 55 observed and the general range of tone intensities gives brilliance to the performance even though through the operation of the step mechanism some of the notes may be 60 sounded more softly. Similarly, when the degree of exhaust in the high exhaust chest is decreased, a feeling of delicacy and moderation may be sensed and the general range 65 of tone intensities is soft although certain notes may stand out above the others.

The foregoing is merely set forth as representative of one of the capacities of the apparatus, although as will be apparent to 65 those skilled in the art, other effects may be

produced in playing either due to the capacity of the apparatus itself or to its combination with the prior art structure.

It is to be understood that the invention is not limited to the embodiment herein shown 70 and described for purposes of illustration, but that on the contrary it may be variously modified and embodied within the scope of the subjoined claims.

I claim as my invention:

1. In an automatic musical instrument having player pneumatics and a source of pneumatic power, in combination, means to govern the pressure applied to said player pneumatics by said source of power to thereby 80 govern playing intensities including a regulator responsive to changes in pressure applied thereto by said source of power, and means to vary by perceptible increments the pressure applied to said governing means 85 by said source of power to thereby additionally govern playing intensities.

2. In an automatic musical instrument having player pneumatics and a source of pneumatic power, in combination, means to govern the pressure applied to said player pneumatics by said source of power to thereby govern playing intensities including a regulator responsive to changes in pressure applied 90 thereto by said source of power, and tracker controlled means to vary by perceptible increments the pressure applied to said governing means by said source of power to thereby additionally govern playing intensities. 95

3. In an automatic musical instrument 100 having player pneumatics and a source of pneumatic power, in combination, means to govern the pressure applied to said player pneumatics by said source of power to thereby govern playing intensities including a 105 regulator responsive to changes in pressure applied thereto, and means to vary by perceptible increments the pressure produced by said source of power to thereby additionally govern playing intensities. 110

4. In an automatic musical instrument having player pneumatics and a source of pneumatic power, in combination, means to govern the pressure applied to said player pneumatics by said source of power to thereby govern playing intensities including a 115 regulator responsive to changes in pressure applied thereto, and tracker controlled means to vary by perceptible increments the pressure produced by said source of power to thereby additionally govern playing intensities. 120

5. In an automatic musical instrument having player pneumatics and a source of pneumatic power, in combination, means to vary by perceptible increments the pressure applied to said player pneumatics to thereby establish a scale of playing intensities; and means to vary by perceptible increments 125 the pressure applied to said pressure vary- 130

ing means to thereby vary incrementally the established scale of playing intensities.

6. In an automatic musical instrument having player pneumatics and a source of 5 pneumatic power, in combination, means to vary by perceptible increments the pressure applied to said player pneumatics to thereby establish a scale of playing intensities; and tracker controlled means to vary by perceptible increments the pressure applied to said pressure varying means to thereby vary incrementally the established scale of playing intensities.

7. In an automatic musical instrument 15 having player pneumatics and a source of pneumatic power, in combination, means to vary by perceptible increments the pressure applied to said player pneumatics to thereby establish a scale of playing intensities; and 20 means to vary by perceptible increments the pressure produced by said source of power to thereby vary incrementally the established scale of playing intensities.

8. In an automatic musical instrument 25 having player pneumatics and a source of pneumatic power, in combination, means to vary by perceptible increments the pressure applied to said player pneumatics to thereby establish a scale of playing intensities; 30 means to vary by substantially continuous progression from any point in said scale the pressure applied to said player pneumatics; and means to vary the pressure produced by said source of power by perceptible increments to thereby vary incrementally the established scale of playing intensities.

9. In an automatic musical instrument having player pneumatics and a source of pneumatic power, in combination, means to 40 vary by perceptible increments the pressure applied to said player pneumatics to thereby establish a scale of playing intensities; means to vary by substantially continuous progression from any point in said scale 45 the pressure applied to said player pneumatics; and tracker controlled means to vary the pressure produced by said source of power by perceptible increments to thereby vary incrementally the established scale 50 of playing intensities.

10. In an automatic musical instrument having player pneumatics and a source of pneumatic power, in combination, means to govern the pressure applied to said player 55 pneumatics to thereby govern playing intensities; means to govern the pressure applied to said governing means to thereby additionally govern playing intensities, comprising a regulator pneumatic having 60 free pneumatic communication with said source of power, and auxiliary means having pneumatic communication with said source of power to control the effective operation of said regulator pneumatic.

65 11. In an automatic musical instrument

having player pneumatics and a source of pneumatic power, in combination, means to govern the pressure applied to said player pneumatics to thereby govern playing intensities; means to govern the pressure applied to said governing means to thereby additionally govern playing intensities, comprising a regulator pneumatic having free pneumatic communication with said source of power, and auxiliary means having tracker controlled pneumatic communication with said source of power to control the effective operation of said regulator pneumatic.

12. In an automatic musical instrument 80 having player pneumatics and a source of pneumatic power, in combination, means to govern the pressure applied to said player pneumatics to thereby govern playing intensities; means to govern the pressure applied to said governing means to thereby additionally govern playing intensities, comprising a regulator pneumatic having free pneumatic communication with said source and auxiliary pneumatic means 85 mounted exteriorly of said regulator pneumatic to control the effective operation thereof.

13. In an automatic musical instrument having player pneumatics and a source of 90 pneumatic power, in combination, means to govern the pressure applied to said player pneumatics to thereby govern playing intensities; means to govern the pressure applied to said governing means to thereby 95 additionally govern playing intensities comprising a regulator pneumatic having free pneumatic communication with said source of power, and auxiliary pneumatic means mounted exteriorly of said regulator pneumatic to control the effective operation thereof.

14. In an automatic musical instrument 100 having player pneumatics and a source of pneumatic power, in combination, means to govern the pressure applied to said player pneumatics to thereby govern playing intensities; means to govern the pressure applied to said governing means to thereby 105 additionally govern playing intensities comprising a regulator pneumatic having free pneumatic communication with said source of power, and auxiliary pneumatic means mounted exteriorly of said regulator pneumatic having tracker controlled pneumatic communication with said source of power and adapted to control the effective operation of said regulator pneumatic.

110 15. In an automatic musical instrument having player pneumatics and a source of pneumatic power, in combination, means to govern the pressure applied to said player pneumatics to thereby govern playing intensities; means to govern the pressure applied to said governing means to thereby 115 additionally govern playing intensities, comprising a regulator pneumatic having pneumatic communication with said source of power, means controlled by said pneumatic 120 to admit atmospheric air to said source of power, and auxiliary means having tracker controlled communication with said source of power to vary effective operation of said regulator pneumatic.

125 16. In an automatic musical instrument having player pneumatics and a source of pneumatic power, in combination, means to govern the pressure applied to said player pneumatics to thereby govern playing intensities.

sities; means to govern the pressure applied to said governing means to thereby additionally govern playing intensities, comprising a regulator pneumatic having pneumatic communication with said source of power, means controlled by said pneumatic to admit atmospheric air to said source of power, and auxiliary pneumatic means mounted exteriorly of said regulator pneumatic to control the effective operation thereof.

16. In an automatic musical instrument having player pneumatics and a source of pneumatic power, in combination, means to govern the pressure applied to said player pneumatics to thereby govern playing intensities; means to govern the pressure applied to said governing means to thereby additionally govern playing intensities, comprising a regulator pneumatic having a fixed leaf and a movable leaf, said pneumatic having pneumatic communication with said source of power, means controlled by said pneumatic to admit atmospheric air to said source of power, connections between said means and the movable leaf of said pneumatic, and means to vary the operative relationship therebetween.

17. In an automatic musical instrument having player pneumatics and a source of pneumatic power, in combination, means to govern the pressure applied to said player pneumatics to thereby govern playing intensities; means to govern the pressure produced by said source of power to thereby additionally govern playing intensities, comprising a regulator pneumatic having a fixed leaf and a movable leaf, said pneumatic having pneumatic communication with said source of power, means controlled by said pneumatic to admit atmospheric air to said source of power, connections between said means and the movable leaf of said pneumatic including auxiliary pneumatics, and tracker controlled means to vary the operation of said auxiliary pneumatics to thereby vary the operative relationship therebetween.

18. In an automatic musical instrument having player pneumatics and a source of pneumatic power, in combination, means to govern the pressure applied to said player pneumatics to thereby govern playing intensities; means to govern the pressure produced by said source of power to thereby additionally govern playing intensities, comprising a regulator pneumatic having a fixed leaf and a movable leaf, said pneumatic having pneumatic communication with said source of power, means controlled by said pneumatic to admit atmospheric air to said source of power, connections between said means and the movable leaf of said pneumatic including a plurality of pneumatics, and means to control the operation of said

last named pneumatics to vary the operative relationship therebetween.

19. In an automatic musical instrument, in combination, a source of pneumatic power including exhauster pneumatics and an exhaust chamber; means to govern the pressure produced by said source of power to thereby govern playing intensities comprising a regulator pneumatic having pneumatic communication with said exhaust chamber; means controlled by said pneumatic to admit atmospheric air to said exhaust chamber; and means to vary the effective operation of said pneumatic.

20. In an automatic musical instrument, in combination, a source of pneumatic power including exhauster pneumatics and an exhaust chamber; means to govern the pressure produced by said source of power to thereby govern playing intensities comprising a regulator pneumatic having a fixed leaf and a movable leaf, said pneumatic having pneumatic communication with said exhaust chamber; means controlled by said pneumatic to admit atmospheric air to said exhaust chamber; connections between said means and the movable leaf of said pneumatic; and means to vary the operative relationship therebetween.

21. In an automatic musical instrument, in combination, a source of pneumatic power including exhauster pneumatics and an exhaust chamber; means to govern the pressure produced by said source of power to thereby govern playing intensities, comprising a regulator pneumatic having a fixed leaf and a movable leaf; means controlled by said pneumatic to admit atmospheric air to said exhaust chamber; connections between said means and the movable leaf of said pneumatic including a plurality of pneumatics; and means to control the operation of said last named pneumatics to vary the operative relationship therebetween.

22. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; and means to vary the pressure produced by said source of power by perceptible increments to thereby vary the established scale of playing intensities.

23. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes

are sounded; and tracker controlled means to vary the pressure produced by said source of power by perceptible increments to thereby vary the established scale of playing intensities.

24. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; means to vary the pressure produced by said source of power by perceptible increments; and means to maintain said pressure at any given incremental level.

25. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; tracker controlled means to vary the pressure produced by said source of power by perceptible increments; and means to maintain said pressure at any given incremental level.

26. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; means to vary by substantially continuous progression the pressure applied to said player pneumatics; and means to vary the pressure produced by said source of power by perceptible increments to thereby vary the established scale of playing intensities.

27. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; means to vary by substantially continuous progression the pressure applied to said player pneumatics; and tracker controlled means to vary the pressure produced by said source of power by perceptible increments to thereby vary the established scale of playing intensities.

28. In an automatic musical instrument having player pneumatics and a source of pneumatic power, in combination, means to vary by perceptible increments the pressure applied to said player pneumatics to thereby

establish a scale of playing intensities; means to maintain the pressure at any given incremental level whether one or many notes are sounded; means to vary by substantially continuous progression the pressure applied to said player pneumatics; and means to vary the pressure produced by said source of power to thereby vary the speed at which said continuous progression variations take place.

29. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; means to vary by substantially continuous progression the pressure applied to said player pneumatics; means to vary the pressure produced by said source of power by perceptible increments; and means to maintain said pressure at any given incremental level.

30. In an automatic musical instrument having player pneumatics and a source of pneumatic power, in combination, means to vary by perceptible increments the pressure applied to said player pneumatics to thereby establish a scale of playing intensities; means to maintain the pressure at any given incremental level whether one or many notes are sounded; means to vary by substantially continuous progression the pressure applied to said player pneumatics; and tracker controlled means to vary the pressure produced by said source of power by perceptible increments; and means to maintain said pressure at any given incremental level.

31. In an automatic musical instrument having player pneumatics and a source of pneumatic power, in combination, means to vary by perceptible increments the pressure applied to said player pneumatics to thereby establish a scale of playing intensities, including a high exhaust chest, a regulated exhaust chest, and a throttle valve therebetween; and variable pressure means acting directly and pneumatically on said throttle valve and operating independently of the pressure of regulated exhaust to thereby vary the established scale of playing intensities.

32. In an automatic musical instrument having player pneumatics and a source of pneumatic power, in combination, means to vary by perceptible increments the pressure applied to said player pneumatics to thereby establish a scale of playing intensities, including a high exhaust chest, a regulated exhaust chest, and a throttle valve therebetween; and tracker controlled variable pressure means operating independently of the pressure of regulated exhaust acting on

said throttle valve to thereby vary the established scale of playing intensities.

33. In an automatic musical instrument having player pneumatics and a source of pneumatic power, in combination, means to vary by perceptible increments the pressure applied to said player pneumatics to thereby establish a scale playing intensities, including a high exhaust chest, a regulated exhaust chest, and a throttle valve therebetween; and means to vary by perceptible increments the pressure in said high exhaust chest acting on said throttle valve.

34. In an automatic musical instrument having player pneumatics and a source of pneumatic power, in combination, means to vary by perceptible increments the pressure applied to said player pneumatics to thereby establish a scale of playing intensities, including a high exhaust chest, a regulated exhaust chest, and a throttle valve therebetween; and tracker controlled means to vary by perceptible increments the pressure in said high exhaust chest acting on said throttle valve.

35. In an automatic musical instrument having player pneumatics and a source of pneumatic power, in combination, means to vary by perceptible increments the pressure applied to said player pneumatics to thereby establish a scale of playing intensities, including a high exhaust chest, a regulated exhaust chest, and a throttle valve therebetween; means to vary by perceptible increments the pressure in said high exhaust chest acting on said throttle valve; and regulator means to maintain the pressure in said high exhaust chest at any given incremental level.

36. In an automatic musical instrument having player pneumatics and a source of pneumatic power, in combination, means to variably govern the pressure applied to said player pneumatics to thereby establish playing intensities, including a high exhaust chest, a regulated exhaust chest, and a throttle valve therebetween; and variable pressure means acting directly and pneumatically on said throttle valve operating independently of the pressure of regulated exhaust to thereby vary additionally the established scale of playing intensities.

37. In an automatic musical instrument having player pneumatics and a source of pneumatic power, in combination, means to govern the pressure applied to said player pneumatics to thereby govern playing intensities, including a high exhaust chest, a regulated exhaust chest, and a throttle valve therebetween; and tracker controlled means to vary the pressure applied to said high exhaust chest to additionally vary playing intensities.

38. In an automatic musical instrument having player pneumatics and a source of

pneumatic power, in combination, means to govern the pressure applied to said player pneumatics to thereby govern playing intensities including a high exhaust chest, a regulated exhaust chest, and a throttle valve therebetween; means to govern the pressure applied to said high exhaust chest to additionally govern playing intensities, comprising regulator means to maintain said pressure at a substantially constant level, and means to vary the action of said regulator to cause it to maintain different degrees of pressure in said chest.

39. In an automatic musical instrument having player pneumatics and a source of pneumatic power, in combination, means to govern the pressure applied to said player pneumatics to thereby govern playing intensities, including a high exhaust chest, a regulated exhaust chest, and a throttle valve therebetween; means to govern the pressure applied to said high exhaust chest to additionally govern playing intensities, comprising regulator means to maintain said pressure at a substantially constant level, and auxiliary pneumatic means having communication with high exhaust to vary the action of said regulator to cause it to maintain different degrees of pressure in said chest.

40. In an automatic musical instrument having player pneumatics and a source of pneumatic power, in combination, means by said source of power to regulate the pressure applied to said player pneumatics to maintain the pressure at a substantially constant level whether one or many notes are sounded; and means to vary the pressure applied to said regulator means by perceptible increments.

41. In an automatic musical instrument having player pneumatics and a source of pneumatic power, in combination, means to regulate the pressure applied to said player pneumatics to maintain the pressure at a substantially constant level whether one or many notes are sounded; and tracker controlled means to vary the pressure applied to said regulator means by said source of power by perceptible increments.

42. In an automatic musical instrument having player pneumatics and a source of pneumatic power, in combination, means by said source of power to regulate the pressure applied to said player pneumatics to maintain the pressure at a substantially constant level whether one or many notes are sounded; means to vary the pressure applied to said regulator means by perceptible increments; and means to maintain the pressure applied at any given incremental level.

43. In an automatic musical instrument having player pneumatics and a source of pneumatic power, in combination, means to regulate the pressure applied to said player

pneumatics to maintain the pressure at a substantially constant level whether one or many notes are sounded; and tracker controlled means to vary the pressure applied to said 5 regulator means by said source of power by perceptible increments; and means to maintain the pressure applied at any given incremental level.

44. In an automatic musical instrument 10 having player pneumatics and a source of pneumatic power, in combination, means to regulate the pressure applied to said player pneumatics including a valve acted on by opposed balanced pneumatic forces acting 15 both directly on said valve and indirectly on said valve through a regulator pneumatic; means to vary the pneumatic force acting directly on said valve by perceptible increments to thereby vary the pressure applied 20 to said player pneumatics, and means to maintain said pneumatic force substantially constant at any given incremental level.

45. In an automatic musical instrument 25 having player pneumatics and a source of pneumatic power, in combination, means to regulate the pressure applied to said player pneumatics including a valve acted on by opposed balanced pneumatic forces acting both directly on said valve and indirectly 30 on said valve through a regulator pneumatic; tracker controlled means to vary the pneumatic force acting directly on said valve by perceptible increments to thereby vary the pressure applied to said player pneumatics, and means to 35 maintain said pneumatic force substantially constant at any given incremental level.

46. In an automatic musical instrument 40 having player pneumatics and a source of pneumatic power, in combination, a valve; a chamber in which pressures are governed thereby; a chamber communicating with said last-named chamber in which pressures are unaffected by said valve, but in which said 45 pressures affect the operation of said valve; and means for varying pressures within the latter chamber by perceptible increments to thereby vary pressures in first-named chamber.

50 47. Expression devices for automatic musical instruments, comprising in combination, a tracker; tracker controlled means for establishing a normal scale of playing intensities; and tracker controlled means for 55 altering by pre-established increments each intensity of the normal scale.

48. Expression devices for automatic musical instruments, comprising, in combination, a tracker; tracker controlled means for establishing a normal scale of playing intensities; and tracker controlled means for altering by a pre-established amount the conditions under which said normal scale is established to thereby cause the establishment 65 of a scale the respective intensities of

which are each different from those of the first scale.

49. In an automatic musical instrument having the usual player pneumatics and source of pneumatic power, in combination, a 70 regulated exhaust chest communicating with said player pneumatic; a high exhaust chest communicating with said source of power; means for selectively establishing in said regulated exhaust chest a series of pressures 75 which will establish a scale of playing intensities, in which the pressure in said high exhaust chest constitutes a factor in such establishment; and means for selectively establishing various degrees of pressure in 80 said high exhaust chest to thereby establish different scales of playing intensities.

50. In an automatic musical instrument having the usual player pneumatics and source of pneumatic power, in combination, 85 a regulated exhaust chest communicating with said player pneumatic; a high exhaust chest communicating with said source of power; means for selectively establishing in said regulated exhaust chest a series of pressures 90 which will establish a scale of playing intensities in which the pressure in said high exhaust chest constitutes a factor in such establishment; and means for altering the pressure in said high exhaust chest to thereby 95 alter the entire scale of playing intensities.

51. Expression controlling devices for automatic musical instruments including a tracker, a pair of pneumatics having connections to openings in said tracker, and means whereby one of said pneumatics is subjected to exhaust and one is open to atmosphere when the controlling openings of the tracker are closed. 100

52. Expression controlling devices for automatic musical instruments including means to govern playing intensities, and means to govern pump pressures to thereby additionally govern playing intensities, tracker controlled valve means to control the operation of said means including a plurality of valve means to set said means for different conditions of operation other than normal, and a single tracker controlled valve means to 105 return said means to position for normal operation.

53. In an automatic musical instrument a source of pneumatic power, comprising, in combination, an exhaust chamber, and a 110 chamber open to atmosphere, means to withdraw air from said exhaust chamber and to spill the air withdrawn to said open chamber, and means whereby air may pass from said open chamber to said exhaust chamber 115 to thereby govern the pressure therein.

54. In an automatic musical instrument a source of pneumatic power, comprising, in combination, an exhaust chamber, and a 120 chamber open to atmosphere, means to with- 125

draw air from said exhaust chamber and to spill the air withdrawn to said open chamber, means whereby air may pass from said open chamber to said exhaust chamber, and 5 means whereby the pressure in said exhaust chamber regulates the flow between said chambers.

55. In an automatic musical instrument a source of pneumatic power, comprising, in 10 combination, an exhaust chamber, and a chamber open to atmosphere, means to withdraw air from said exhaust chamber and to spill the air withdrawn to said open chamber, means whereby air may pass from said open chamber to said exhaust chamber, a 15 valve for governing the flow of air therebe-

tween, means operated by the exhaust in said exhaust chamber for controlling said valve, and means for varying the operation of said means. 20

56. In an automatic musical instrument a source of pneumatic power, comprising, in combination, an exhaust chamber and a chamber open to atmosphere, bellows means to withdraw air from said exhaust chamber 25 at a substantially constant rate, and means whereby air may pass from said open chamber to said exhaust chamber at varying rates.

In testimony whereof, I have signed my name to this specification this 7th day of 30 March, 1924.

CHARLES F. STODDARD.
